(57) **CLAIM**

The ornamental design for a plant container, as shown and described.

DESCRIPTION

FIG. 1 is a rear elevation view of a plant container showing our new design;

FIG. 2 is a front elevation view thereof; and,

FIG. 3 is a top plan view thereof.

The broken lines depict environmental subject matter only and form no part of the claimed design.

1 Claim, 3 Drawing Sheets

FIG. 1

FIG. 2

FIG. 3
